BLASTING CARTRIDGE

George A. Merchant, Chicago, and Roland
Milan, Pinckneyville, Ill., assignors to Binkley
Coal Company, Chicago, Ill., a corporation of
Illinois

Application April 8, 1935, Serial No. 15,198

12 Claims. (Cl. 102—6)

Our invention relates to improvements in blasting cartridge and has for one object to provide a new and improved form of liquid oxygen carbon blasting cartridge which will be stiff for handling, 5 sufficiently rigid to pack in the blasting hole, have long life and will be easily filled, impregnated, manipulated and discharged and which will have high explosive effect. Other objects of our invention will appear from time to time 10 throughout the specification and claims.

Our invention is illustrated more or less diagrammatically in the accompanying drawing, wherein—

Figure 1 is a side elevation;

Figure 2 is a section along the line 2—2 of Figure 1;

Figure 3 is a side elevation of one of the reinforcing strips.

Like parts are indicated by like characters throughout the specification and drawing.

1 is a generally cylindrical canvas bag having a tapered closed end 2. Contained within the cylindrical portion of the bag is an inner cylindrical bag 3 terminating at a distance from the closed end of the outer bag substantially equal to the length of the tapered portion and extending outwardly beyond the outer bag to provide a filling portion collapsible as a handle as indicated at 4. Thus the inner and the outer bags are in register 20 for a portion of their length giving throughout the cylindrical portion of the cartridge a double thickness layer. The inner and outer bags are joined together by longitudinal seams 5. The outer bag is somewhat larger than the inner bag 25 so that the seams 5 define longitudinal pockets between the inner and the outer bag. In these longitudinal pockets are contained relatively stiff reinforcing strips 6 which are made preferably of celotex or other similar material, and are of 30 such width that they do not entirely fill the bag and of such thickness that a dead air space is defined between the seam, the inner and outer bag and each edge of the stiffening strip. The stiffening strips also extend only throughout the cylindrical portion of the bag. 7 is a carbon filler made 35 of carbon black, lamp black, charcoal or any other similar finely divided carbonaceous material and packed into the bag to distend it to the shape shown in Figure 1, the bag being filled with this material.

8 is a detonator embedded in the carbonaceous filler. 9 indicates a blasting fuse extending from the detonator out through the bag and through the handle 4. This fuse may take the form of a wire if the detonator is electric or merely a com-

bustible fuse if the detonator is not electric. 10 is a copper tie ring closing the bag and holding the contents and the fuse snugly in position. The dead air spaces above referred to are indicated at 11 and it will be noted that normally there are two 5 dead air spaces in each pocket.

In use, the bag assembled as indicated, has the celotex or similar stiffening strips thrust into the pockets and is then filled with the carbonaceous filling material, the detonator being inserted 10 thereafter and the copper tie applied to hold the contents of the bag, the detonator and fuse in proper relationship with the collapsed portion of the bag furnishing the handle by which the cartridge may be manipulated. The contents of the 15 bag is packed in tight enough so as to make a reasonably stiff cartridge. The tapered end is sufficiently tapered so that it needs no reinforcing. The long cylindrical portion is flexible enough so that the "celotex" or other strips are 20 needed to maintain it in alignment.

The entire assembled cartridge is then inserted in a bath of liquid oxygen which penetrating the cartridge through the fabric or canvas of the bag and the "celotex" strip completely impregnates 25 them also, though under some circumstances other strips such as paper board, which is not absorbent of liquid oxygen, may be used. The desirability of the use of "celotex" is that the space in the cartridge sacrificed to stiffening the cartridge 30 is still under these circumstances available to contain part of the explosive charge.

When fully impregnated, the cartridge is withdrawn from the bath, packed in the shot hole and detonated to cause explosive combination of the 35 liquid oxygen and the carbonaceous material including the "celotex". The "celotex" has a triple function. It stiffens the cartridge, it furnishes an insulation to prevent heating of the cartridge and so evaporation of the cold liquid oxygen and 40 it furnishes a material to combine with some of the oxygen when explosion takes place. The dead air spaces along the edge of each of the celotex strips serve as insulation only to prevent heat absorption and so evaporation of the liquid 45 oxygen. When something other than "celotex" or similar materials are used, then the faculty of supporting combustion is sacrificed and also the rate at which absorption of liquid oxygen is 50 sacrificed because the "celotex" being pervious permits the liquid oxygen to penetrate throughout the entire superficial area of the cartridge as distinguished from devices heretofore used where stiffening means were available which had to be 55 perforated or special apertures had to be pro-

vided to permit ingress of liquid oxygen, thereby decreasing the rate of speed of saturation.

Another advantage of the double cloth lining is that if in thrusting the cartridge into the blasting hole the bag is torn, it will be only the outermost bag that will be torn, the inner bag will be held normally intact and the carbon will not be wasted. Moreover in dealing with a wet hole, the presence of the two layers of cotton or fabric with the air space between, insures longer life of the cartridge because what happens is that an ice jacket will form on the outer bag and serve as an insulation to protect the inner bag.

15 We have in connection with the description of our invention suggested the use of "celotex" or a similar material because this is an especially well-known type of material which is suitable for our purpose. It is suitable because it is fibrous, felt-like and is made of combustible fiber and so has structural strength while being permeable to liquid oxygen. Many other types of artificial wood or material of that general character having the permeability, the fibrous structure and the combustible features might be used.

We claim:

1. A blasting cartridge comprising, a fabric bag, a plurality of longitudinally extending peripherally disposed and spaced reinforcing members contained therein, the combined width of which is materially less than the peripheral length of the bag, a carbonaceous filler for the bag, the filler and the reinforcing members being both impregnated with liquid oxygen.

2. A blasting cartridge comprising, a fabric bag, a plurality of longitudinally extending peripherally disposed and spaced air pockets contained therein, a reinforcing member contained within each pocket extending throughout the length thereof, the width of the member being materially less than the width of the pocket.

3. A blasting cartridge comprising, inner and outer fabric bags joined along longitudinal lines to form peripherally disposed air pockets, the circumferential length of the inner fabric bag being materially less than the circumferential length of the outer bag.

4. A blasting cartridge comprising, inner and outer fabric bags joined along longitudinal lines to form peripherally disposed air pockets, reinforcing members contained within said air pockets and extending substantially throughout the length thereof, the width of the reinforcing members being materially less than the width of the pockets in which they are located, air chambers being formed within the reinforcing pockets between the edges of the reinforcing members and the boundaries of the pockets.

60 5. A blasting cartridge comprising, inner and outer fabric bags, the inner bag being somewhat smaller than the outer, the bags being joined along a plurality of spaced longitudinal lines to form air pockets between them, the circumferential length of the inner fabric bag being materially less than the circumferential length of the outer bag.

65 6. A blasting cartridge comprising, inner and outer fabric bags, the inner bag being somewhat smaller than the outer, the bags being joined along a plurality of spaced longitudinal lines to form air pockets between them, longitudinally

disposed reinforcing members contained one within each pocket and extending substantially throughout the length thereof, the width of the reinforcing members being materially less than the width of the pockets in which they are located, air chambers being formed within the reinforcing pockets between the edges of the reinforcing members and the boundaries of the pockets.

7. A blasting cartridge comprising, an inner and outer fabric bag, the outer bag tapering in one direction beyond the inner bag to a closed end, the inner bag extending beyond the opposed end of the outer bag and collapsible to form a handle.

8. A blasting cartridge comprising, an inner and outer fabric bag, the outer bag tapering in one direction beyond the inner bag to a closed end, the inner bag extending beyond the opposed end of the outer bag and collapsible to form a handle, the two bags being joined along longitudinal lines to define air pockets between them.

9. A blasting cartridge comprising, an inner and outer fabric bag, the outer bag tapering in one direction beyond the inner bag to a closed end, the inner bag extending beyond the opposed end of the outer bag and collapsible to form a handle, the two bags being joined along longitudinal lines to define air pockets between them and reinforcing strips contained within the air pockets and extending throughout their length.

10. A carbon oxygen cartridge comprising, a fabric bag adapted to contain a supply of carbonaceous material, longitudinally extended reinforcing strips located about the periphery of the bag and spaced one from another, the reinforcing strips being pervious and absorbent of liquid oxygen.

11. A carbon oxygen cartridge comprising, a fabric bag adapted to contain a supply of carbonaceous material, longitudinally extended reinforcing strips located about the periphery of the bag and spaced one from another, the reinforcing strips being formed of relatively thick slabs of fibrous combustible material permeable to liquid oxygen and having structural strength and the like.

12. A blasting cartridge comprising an outer fabric bag having a cylindrical portion and a relatively short tapered closed end, a lining bag contained therein extending thereinto substantially the length of the cylindrical portion and extending therebeyond at the rear to collapse and furnish a handle, the inner bag being slightly smaller than the outer, the two bags being joined along parallel longitudinal lines to provide longitudinal pockets extending the length of the cylindrical portion, stiffening strips of fibrous combustible material permeable to liquid oxygen and having structural strength or the like contained within the pockets and extending throughout the length of the cylindrical portion of the bag, a carbonaceous filler contained within and distending the bag, a detonator embedded in the carbonaceous filler, a fuse extending out through the neck of the bag, a tie adapted to hold the collapsed end of the bag snugly about the fuse, the bag, the contents and the celotex lining being all impregnated with liquid oxygen.
